LOCK MEANS FOR STEERING-GEAR.

1,117,510.

Specification of Letters Patent. Patented Nov. 17, 1914.

Application filed December 4, 1913. Serial No. 804,736.

To all whom it may concern:

Be it known that we, JOHN A. MALONE and LEE ROY MALONE, citizens of the United States, residing at Los Angeles, in the county of Los Angeles and State of California, have invented certain new and useful Improvements in Lock Means for Steering-Gear, of which the following is a specification.

10 Our invention relates to improvements in apparatus for preventing the fraudulent operation or use of automobiles or similar vehicles, and has particular reference to novel means for holding or locking the steering mechanism or gear thereof against movement.

An important object of the invention is to provide means of the above mentioned character, which are simple in construction, inexpensive to manufacture, sufficiently strong to withstand the strains to which the same is subjected, and convenient in use.

Other objects and advantages of this invention will be apparent during the course of the following description.

In the accompanying drawings forming a part of this specification and in which like numerals are employed to designate like parts throughout the same, Figure 1 is a 30 side elevation of apparatus embodying our invention, showing the same in use, Fig. 2 is a perspective view of a locking arm included in the apparatus, Fig. 3 is a sectional view taken on line 3-3 of Fig. 1, Fig. 4 is a side elevation of the apparatus, showing a slightly modified use of the same, Fig. 5 is a side elevation of a slightly different form of my invention, Fig. 6 is a perspective view of a locking arm embodied therein, Fig. 7 is a sectional view taken on line 7-7 of Fig. 5, Fig. 8 is a sectional view taken on line 8-8 of Fig. 9, Fig. 9 is a transverse section taken on line 9-9 of Fig. 8, Fig. 10 is a fragmentary side elevation of one end of the clamping sleeve, Fig. 11 is a section on line 11-11 of Fig. 7, and, Fig. 12 is a side elevation of the apparatus, showing a slightly different use of the same.

In the drawings, wherein for the purpose 50 of illustration is shown preferred embodiments of our invention, attention being first called to Figs. 1 to 4 inclusive, the numeral 5 designates a rotatable steering rod, mounted in a relatively stationary tube or casing 6, as is customary. The steering rod

5 is connected with the front steering wheels of an automobile, by any well known or preferred means, (not shown). Rigidly connected with the upper end of the steering rod 5 is an operating element or steering wheel 7, including spokes 8, as shown. Rigidly mounted upon the relatively stationary casing 6 is a sleeve 9, attached thereto by means of screws 10 or the like. Any other suitable means may be employed to 65 clamp or lock the sleeve 9, to the casing 6, as desired. Formed upon one side of the sleeve 9 is a pair of spaced relatively long guide and reinforcing plates or flanges 11, extending longitudinally of the sleeve 9, 70 preferably for its entire length. These plates or flanges 11 afford a longitudinal opening or channel 12, for receiving a longitudinally movable or reciprocatory arm or rod 13, having slideable engagement with the inner walls of the plates or flanges, as more clearly illustrated in Fig. 3. The arm or rod 13 is provided near its lower end with an elongated slot 14, receiving a transverse pin or bolt 15, attached to the plates or 80 flanges 11, as shown. It is thus seen that the arm, or rod 13 is pivotally connected with the plates or flanges 11 and is free to be moved longitudinally between the same, such plates or flanges serving to guide the 85 arm 13 in its movements and to reinforce and strengthen the same, removing the strains from the pin or bolt 15 and compensating for the weakening of the arm 13 by the slot 14. Connected with the upper or 90 outer end of the arm or rod 12, and preferably cast integral therewith, is an L-shaped head 16, to which is hinged, as shown at 17, a horizontal arm 18. The outer end of this arm 18 is preferably forked for receiving a 95 bolt 19 pivoted thereto, adapted for insertion through an opening 20 formed in the horizontal arm of the L-shaped head 16. The free end of the bolt 19 is apertured, as shown at 21, for receiving a padlock 100 22 or the like. In the use of this form of the invention, the bolt 19 is removed from the opening 20, which may be readily accomplished by swinging the arm 18 upwardly, whereby the spoke 8 of the wheel 105 7 may be inserted within the L-shaped head 16 and locked therein, as is obvious from Fig. 2. By having the arm or rod 13 longitudinally movable, it is obvious that the same may be moved toward or away from 110

the steering wheel 7, thus rendering it convenient to connect the arm with the steering wheel. The arm or rod 13 may be quickly and conveniently disconnected from the steering wheel by removing the pad-lock 22 and moving the arm 13 longitudinally downwardly, the arm 18 being automatically swung upwardly and the bolt 19 withdrawn from the opening 20. It is obvious that by proper manipulation of the arm or rod 13, the same may be swung downwardly out of the way. Great difficulty has heretofore been encountered in connection with devices along this line, which has been due to the fact that such structures are ordinarily not strong enough, but when constructed sufficiently strong they become too clumsy. We overcome this disadvantage by the provision of the plates or flanges 12, which lend strength and rigidity to the arm or rod 13.

In Fig. 4, the sleeve 9 is rigidly mounted upon a rotatable steering rod 23, journaled in a fixed bearing 24, as shown. The rod 23 is turned by a hand-wheel 25, as is customary. The arm or rod 13 is connected with the sleeve 9 and in identically the same manner, but the free end thereof is detachably connected with a fixed bracket 26, arranged adjacent the lower end of the steering rod 23, as shown. The means to connect or lock the arm or rod 13 with the fixed bracket 26 are identical with those already described for connecting the rod 13 with the wheel 7. In this use of the invention, it is obvious that when the arm 13 is connected or locked with the stationary bracket 26, the same will hold the steering rod 23 against turning movement, other parts of the apparatus operating in the same manner as pointed out in connection with the first use of the invention.

In Figs. 5 to 12 inclusive, we have shown a slightly different form of the invention. In these figures, the numeral 27 designates a relatively stationary tube or casing, within which is rotatably mounted a steering rod 28. Rigidly connected with the upper end of this steering rod is a steering wheel 29. Surrounding the casing 27 is circumferentially expandable and contractible clamping sleeves or rings 30, as shown in detail in Figs. 8 and 9. This sleeve 30 is connected with a casting or body portion 31, in the manner to be next described. The body portion 31 has an inner concave surface 32, provided with recesses 33. One end of the sleeve 30, which is suitably flexible, is passed into one end of the concave surface 32 of the portion 31, the same being arranged between inwardly extending guide fingers 34, as more clearly shown in Fig. 8. The sleeve 30 is provided at one end with a lateral extension or hook 35, adapted for insertion within a selected one of the recesses 33, whereby the sleeve 30 may be adjustably

connected with the body portion 31. The opposite end of the sleeve 30 extends into the concave face 32 and passes between guide fingers 36, as more clearly shown in Fig. 8. This end of the sleeve 30, as more clearly shown in Fig. 10, is provided with a thickened transverse portion 37, having an opening 38 therebelow. The thickened transverse portion 37 is provided with a screw-threaded opening 39, receiving the screw-threaded end of a clamping or adjusting screw 40, which is rotatably mounted within an opening 41 formed through a longitudinally extending guide flange or plate 42, carried by the body portion 31 and preferably cast integral therewith. The head of the screw 40 extends into an opening or recess 43. It is thus seen that the sleeve 30 may be first adjusted by placing the lateral extension 35 within the proper recess 33 and the body portion 31 may be clamped to the sleeve 27 by rotation of the screw 40. The longitudinally extending reinforcing flange or plate 42 has its upper end preferably curved laterally outwardly slightly, as more clearly shown in Fig. 5. The numeral 44 designates a locking arm, which is preferably elliptical in cross-section, with its greatest diameter extending at a right angle to the radius of the steering wheel 29. The lower end of the arm 44 is forked, providing spaced tines 45, which straddle the guide flange or plate 42 and are preferably provided with longitudinal slots 46. Arranged slightly below the recess 43, as more clearly shown in Fig. 7, is a transverse opening 47, receiving a bolt 48, which passes into the slots 46, to pivotally connect the arm 44 with the guide flange or plate 42. It is thus seen that the arm 44 may be swung in a vertical plane and also moved longitudinally. The function of the flange or plate 42 is to guide the arm 44 in its swinging and longitudinal movements and to reinforce the same laterally.

The upper end of the arm 44, as more clearly shown in Fig. 6, is provided with an approximately L-shaped head 49, including a horizontal arm 50 and a vertical arm 51, arranged at approximately a right angle with relation to each other. The horizontal arm 50 is preferably provided with a V-shaped recess 52. Pivotally connected with the upper end of the vertical arm 51, as shown at 53, is a vertically swinging arm 54, the free end of which is forked and is pivotally connected, as shown at 55, with a depending lug 56. This lug extends through an aperture 57 in the free end of the horizontal arm 50. The extreme lower end of the lug 56 is apertured for receiving an element or pad-lock 58 or the like.

In Fig. 10, the apparatus is shown as used in a slightly different manner. In this figure the guide and reinforcing flange or

plate 42 is inverted and is rigidly mounted upon a steering rod 59, turned by a wheel 60. The arm 44 is detachably connected with a relatively stationary bracket 61. The 5 connecting means between the arm 44 and the bracket 60 are identical with those hereinabove described, between the arm 44 and the wheel 29, and it is thought unnecessary to recite the same again.

10 The operation of the second form of the invention is so similar to the first, already given, that it is thought that no further explanation of the same is necessary, except to state that when the arm 44 is in its operative position it covers recess 43, preventing 15 the improper rotation of the screw 40.

It is to be understood that the forms of our invention herewith shown and described are to be taken as preferred examples of the 20 same, and that various changes in the shape, size and arrangement of parts may be resorted to without departing from the spirit of the invention or the scope of the subjoined claim.

25 Having described our invention, we claim:—

The combination with a plurality of relatively rotatable elements, of a swinging arm connected with one element and provided 30 near its free end with an approximately L-

shaped head embodying longitudinal and transverse arms, said transverse arm extending in one direction beyond the movable arm for a substantial distance and provided with a vertical opening formed therethrough, a normally approximately horizontally arranged strip having one end hinged to the upper end of the longitudinal arm of the approximately L-shaped head and adapted to assume a position substantially parallel with said transverse arm, a bolt adapted to be arranged substantially parallel with said longitudinal arm and having its upper end hinged to the free end of said strip and its lower end apertured 45 and adapted to be passed through the opening in said transverse arm to extend downwardly beyond the same for a substantial distance, and an element to be inserted through the aperture in the bolt to prevent 50 the bolt from being withdrawn from the opening in the transverse arm.

In testimony whereof we affix our signatures in presence of two witnesses.

JOHN A. MALONE.
LEE ROY MALONE.
